DECANTER BOTTLE

Ernest Du Pree, Old Greenwich, Conn., assignor
to Schenley Industries, Inc., New York, N. Y., a corporation of Delaware

Application June 20, 1950, Serial No. 10,660

Term of patent 14 years

(Cl. D58—8)

To all whom it may concern:

Be it known that I, Ernest Du Pree, a citizen of the United States of America, residing at city of Old Greenwich, county of Fairfield, and State of Connecticut, have invented a new, original, and ornamental Design for Decanter Bottle, of which the following is a specification, reference being had to the accompanying drawing, forming part thereof:

I claim:

The ornamental design for a decanter bottle, as shown.

ERNEST DU PREE.
